United States Patent Office

Des. 226,303
Patented Feb. 13, 1973

226,303

BOTTLE

Edward J. Kretz, 2120 Marlow, Toledo, Ohio 43606

Filed Oct. 6, 1971, Ser. No. 187,233

Term of patent 14 years

Int. Cl. D9—01

U.S. Cl. D9—66

FIG. 1

FIG. 2

FIG. 4

FIG. 3

FIG. 5

FIG. 1 is an elevational view of a bottle showing my new design, the opposite side being a mirror image of the side shown;

FIG. 2 is an elevational view looking from the right of FIG. 1;

FIG. 3 is an elevational view looking from the left of FIG. 1;

FIG. 4 is a top plan view; and

FIG. 5 is a sectional view taken on the line 5—5 of FIG. 2.

I claim:

The ornamental design for a bottle, substantially as shown and described
